UNITED STATES PATENT OFFICE.

CHARLES T. DRAPER, OF CLEVELAND, OHIO, ASSIGNOR TO THE DRAPER MANUFACTURING COMPANY, OF CLEVELAND, OHIO, A CORPORATION OF OHIO.

REVERSIBLE FAUCET AND BUNG.

1,070,880.

Specification of Letters Patent. Patented Aug. 19, 1913.

Application filed March 2, 1912. Serial No. 681,191.

To all whom it may concern:

Be it known that I, CHARLES T. DRAPER, a citizen of the United States, residing at Cleveland, in the county of Cuyahoga and State of Ohio, have invented certain new and useful Improvements in Reversible Faucets and Bungs, of which the following is a specification.

My invention relates to improvements in a reversible faucet and bung, and has for its object the construction of a device of this character which shall be self-locking and especially adaptable for use in connection with sheet metal containing-vessels. Prior to the introduction of this class of containers, it was quite commonly necessary to transfer many liquids from the barrels employed for transportation, to metallic receptacles or tanks, but at the present time several advantages are attained by using the sheet metal containing-vessels for storing and dispensing the contents thereof. One disadvantage previously experienced with the combined faucets and bungs, has been the accidental opening of the faucet-valve during shipment or storage, so that leakage ensues. Again, the prior devices with which I am acquainted; were of such depth that they were not well adapted to use with the ordinary sheet metal containing-vessel. Having these features in mind, it has been my endeavor to construct a practical and serviceable reversible faucet and bung which, in addition, may be interchanged with the usual screw-plug, should the former be mislaid or broken. The features thereof may be readily explained in connection with the accompanying sheet of drawings, wherein:—

Figures 1 and 2 are fragmentary views in vertical section, illustrating a sheet metal containing-vessel, wherein the combined faucet and bung are shown in its two reversible positions; Fig. 3 is a fragmentary end view of the container showing the faucet in its inner or reversed position and provided with a cover-cap partly broken away; Fig. 4 is an enlarged view partially in longitudinal section, illustrating the reversible faucet and bung in more detail, for the purpose of emphasizing the self-locking feature, and Fig. 5 shows a modification of the faucet-member also adapted to make the same self-locking.

Throughout the several figures of the

drawings, I have employed the same character of reference to indicate similar parts.

In the steel container *a* shown in the drawings, the head *b* thereof is recessed at its bung-hole *c*. This recess accommodates the shallow exterior bushing *d*, which is welded about said bung-hole. The bushing is threaded both exteriorly and interiorly for the purpose of accommodating respectively a screw-cap *e* and the ordinary screw-plug (not shown).

The reversible faucet and bung *f*, best shown in Fig. 4, is secured upon said bushing against the gasket *g*, by means of the threaded annular cap *e*. For the purpose of guarding against the entrance of dirt during storage and shipment, a sheet metal cover *h* may be interposed between said cap and the flange *f'* of the faucet, when the latter is in its reversed position. The faucet *f* provided with a transversely bored valve-part *f''* and a T-handle *f'''* at right angles to the bore or opening of said valve-part, are all proportioned, so that they may readily pass through the bushing. The latter, although quite shallow, is of sufficient depth, however, so that the one end of the handle *f'''* extends within said bushing when the faucet is inserted, for the purpose of making the device self-locking. It is quite obvious that with the handle in this position, no amount of jarring, irrespective of the loose fit of the valve-part, will permit the same to turn, and thus prevents leakage.

Another modification is shown in Fig. 5, wherein the faucet is provided with a forward lug *f⁴*, adapted to defeat the forward rotation of the single handle-member *f⁵*, thus preventing the reversal of the faucet-member unless the handle is turned into its self-locking position. Other means may be employed to attain this same result, but the simplest and most advantageous forms, I believe, are herein shown and described.

Having now set forth the features of my invention, I claim and desire to secure by Letters-Patent, the following:

1. The combination with a containing-vessel, of a bushing attached at the bung-hole thereof, a combined faucet and bung reversible with respect to said bushing; said faucet being provided with a rotatable valve-part, and an actuating handle extending in both directions substantially parallel

with the faucet body in the closed position 5 of said valve-part and also within the bushing when the faucet is reversed, and means for securing said faucet in either of its reversible positions, substantially as set forth.

2. The combination with a sheet metal receptacle, of a bushing secured at the bung-hole thereof, a reversible faucet and bung having a flange fitting over said bushing, 10 and a T-handled valve-part with its opening at right angles to said T-handle; the bushing being of sufficient depth to engage one end of the T-handle in the reversed and closed position of said faucet-member, and 15 a screw-threaded cap adapted to secure the flange of said faucet and bung in either of its reversible positions, substantially as set forth.

3. The combination with a closed containing-vessel, having a bung-hole, of a 20 combined faucet and bung reversible with respect to the bung-hole; said faucet being equipped with a rotatable valve-part, and means for locking the same in its closed position.

sition when the faucet is inserted within 25 said vessel, and additional means for securing the faucet in either of its reversible positions, substantially as set forth.

4. The combination with a sheet metal receptacle, of a bushing welded about the 30 bung-hole thereof, a reversible faucet and bung associated with said bushing; the same being equipped with a rotatable valve-part, a handle therefor adapted to extend within the bunghole and lock the valve 35 when said member is in its reversed position, and means for preventing such reversal of the member with the valve-part in its open position, and additional means for securing said faucet in its reversed position, substantially as set forth. 40

In testimony whereof I affix my signature in presence of two witnesses.

CHARLES T. DRAPER.
